UNITED STATES PATENT OFFICE.

JOHN P. SYKES, OF WALLINGFORD, AND HARMON E. STOVER, OF PHILADELPHIA, PENNSYLVANIA, ASSIGNORS TO THE BALDWIN LOCOMOTIVE WORKS, OF PHILADELPHIA, PENNSYLVANIA, A CORPORATION OF PENNSYLVANIA.

JIG FOR ASSEMBLING LOCOMOTIVE FRAMES.

Application filed April 6, 1922. Serial No. 550,015.

To all whom it may concern:

Be it known that we, JOHN P. SYKES and HARMON E. STOVER, citizens of the United States, residing, respectively, in Wallingford, Delaware County, Pennsylvania, and Philadelphia, Pennsylvania, have invented certain Improvements in Jigs for Assembling Locomotive Frames, of which the following is a specification.

10 Our invention relates to certain improvements in jigs for assembling the frames of a locomotive so that, when the frames are brought in alignment and firmly secured to the jig, parts of the locomotive can be accurately applied to the frames.

15 One object of the present invention is to design the jig so that the frames can be supported at the openings for the journal boxes and the frames, with the parts attached thereto, can be removed bodily from the jigs when the cap plates of the frames are removed,

20 A further object of the invention is to extend the foundation plate from the saddles so that the jacks can be adjustably mounted on the plate.

25 In the accompanying drawings:

Fig. 1 is a plan view of our improved jig, showing the frames of a locomotive mounted thereon;

30 Fig. 2 is a side view of Fig. 1;

Fig. 3 is a sectional view on the line 3—3, Fig. 1, showing one of the saddles;

35 Fig. 4 is an end view of Fig. 3;

Fig. 5 is an end view of the upper portion of the jig, the view being taken on the side opposite to that illustrated in Fig. 4;

40 Fig. 6 is a plan view of the saddle shown in Fig. 3;

Fig. 7 is a sectional view on the line 7—7, Fig. 1;

Fig. 8 is a sectional view on the line 8—8, Fig. 7;

Fig. 9 is a plan view of Fig. 8;

45 Fig. 10 is an enlarged view showing one of the locomotive frames secured to one of the brackets of the saddles; and

Fig. 11 is a sectional view on the line 11—11, Fig. 10.

Referring to the drawings, 1 is the foundation plate extending substantially the full length of a locomotive frame, which is illustrated at a—a. 2 are saddles mounted on the foundation plate. 3 are transverse base plates located at each end of the foundation plate in the present instance. Mounted on the base plates are jacks 4. These jacks support the overhanging ends of the locomotive frames. The foundation plate has two grooves 5 extending throughout its length and the saddles have projecting ribs, which extend into the grooves. The base 8 of each saddle is secured to the foundation plate by bolts 9, as clearly shown in Fig. 3. The base plates 3 for the jacks have projections 7 adapted to the grooves 5 and are held in position by bolts 10. By this construction, the saddles can be moved to any position desired on the foundation plate and the base plates 3 can also be moved to accommodate frames of different sizes. Each base plate has a longitudinal groove 11 and the base 12 of each jack 4 has a projection 13 adapted to the grooves. In the present instance, the base plates have a series of cavities 14 in the bottom of the grooves 11 so that a pinch bar can be used to adjust the jacks in proper alignment with the frame. Each jack is provided with the usual screw 15 having a swivel head 16. The screw can be turned to raise and lower the head, as desired.

45 The particular construction of the jack structure is claimed in an application for patent filed by us even date herewith.

The saddles 2 are made as shown in Figs. 3 to 6, inclusive. The standard 17 of the saddles is made solid and projects from the base 8 and is less in width than the space between the frames of the locomotive which are to be assembled on the saddles. Projecting from one end of each saddle is a bracket 18 and projecting from the opposite end of each saddle is a bracket 19. The bracket 19 is of greater length than the

bracket 18. These brackets are of such a size that they can extend through the journal box openings in the locomotive frames. the dot and dash line *a*, Figs. 3 and 4, shows 5 one of the largest frames and the dotted line *b* shows one of the smallest frames.

On the bracket 18 of each saddle is a shoulder 20. This shoulder forms an abutment for the frames at one side of the locomotive, irrespective of the size of the frame. 10 This abutment is the guide for assembling all of the frames.

When a frame is mounted in position on the saddles 18, the straight pedestal *c* of the 15 frame is forced against the side 21 of the bracket by the screws 22, which is adjusted to fit against the opposite pedestal *d* of the frame, Fig. 2. Blocks may be used to fill the space, if the pedestals are spaced a considerable distance apart. This locks the frame rigidly in position. Then another frame is placed on the brackets 19 and spacing bars 23 are used to space the frames properly, and, when they are spaced, as 20 shown by dotted lines, Fig. 3, they are held in position by the screws 24, which are similar to the screws 22. This screw may be located in any one of the three cavities 25 in the bracket 19, according to the distance 30 apart of the frames of the locomotive being assembled.

Each bracket is chamfered at 26 to accommodate different fillets at the corner between a pedestal and the upper portion of 35 the frame.

In order to secure the frame on the brackets 18 against the abutment 20, a clamp plate 27 is provided, held by a screw 28, Figs. 5, 10 and 11, and blocks 29 and 30 are 40 adapted to channels in each bracket. These blocks press against the outside of the frame so that, on turning the screw 28, the frame is held firmly against the abutment 20. The spacing bars 23 hold the other frame in 45 proper position. The several parts of a locomotive are assembled on the frames, then the cap plates *e* are removed and the frames, with the parts attached, can be raised bodily clear of the saddles.

50 In some instances, when a frame is of considerable length, an intermediate support 31 may be located on the foundation plate so as to provide an intermediate support between the saddles, as shown clearly in Figs. 55 1 and 2.

It will be seen by the above construction 60 that the saddles and jacks can be located so as to support the frames of a locomotive properly, the saddles being adjusted so that their brackets will extend through the journal box openings formed by the pedestals of the frame. The side of the straight pedestal is used to align the first frame located on the brackets 18. This frame is held firmly 65 in position against the shoulder 20 by clamps

and against the side of the straight pedestal by screws 22. Then the other frame is properly aligned on the brackets 19 so as to be directly opposite the frame on the brackets 18. This frame is clamped in position by the screws 24. Then the several parts of the locomotive can be assembled on these frames, after which the frames, with the assembled parts, can be bodily removed from the jigs by detaching the cap plates *e*. 75

We claim:

1. The combination in a jig for assembling locomotive and other frames, of saddles, each saddle having a standard; and a bracket projecting at each end of the standard and shaped to extend into an axle box space of the frames and of such a width that, when the cap plates, which close the bottoms of these spaces, are removed, the frames, with the assembled parts thereon, can be raised 85 clear of the saddles.

2. The combination of a foundation plate; saddles mounted on the plate, said saddles being arranged to support the side frames of a locomotive; and adjustable jacks arranged to support the overhanging ends of the frames of a locomotive. 90

3. The combination of a foundation plate: saddles adjustably mounted thereon; base plates; and jacks adjustably mounted on the 95 base plates, said jacks being arranged to support the overhanging portions of a locomotive frame.

4. The combination of a foundation plate; 100 saddles mounted thereon, each saddle having a standard; a bracket at each end of the standards; and means for clamping one of the side frames of a locomotive rigidly to one bracket, the other bracket being extended so that the other frame of the locomotive can be positioned on said bracket and clamped thereto to align with the frame on the other bracket. 105

5. The combination of a base plate having 110 longitudinal grooves therein; saddles having projections adapted to the grooves; means for adjustably securing the saddles to the foundation plate; a bracket at one end of each saddle, said bracket having shoulders; means on the brackets for securing a locomotive frame against the shoulders and against one side of the brackets; an extended bracket at the opposite end of the standard; and means for securing a side frame of a locomotive on these brackets so as to 115 align with the frame on the first mentioned brackets. 120

6. The combination in a jig for assembling 125 locomotive frames, of saddles, each saddle having a standard; brackets extending from the ends of the standards, said brackets being arranged to support the frames of a locomotive; a shoulder on one of said brackets; a clamp on the end of the bracket; blocks adapted to be located between a frame and 130

the clamp plate; and a screw for applying pressure to the clamp plate to secure the frame firmly to each bracket.

7. The combination in a jig for assembling the frames of a locomotive, of a foundation plate; saddles thereon, each saddle having a standard; brackets extending from each end of each standard, the width of the stand-

ards being less than the spaces between the frames of a locomotive, and means for aligning the frames on the saddles so that, when the parts of a locomotive are assembled on the frames, the frames can be raised off of the saddles in a straight line. 10
